United States Patent Office.

C. O. HANSEN, OF MEMPHIS, TENNESSEE.

Letters Patent No. 79,069, dated June 23, 1868.

IMPROVEMENT IN BEVEL-SQUARES.

The Schedule referred to in these Letters Patent and making part of the same.

TO ALL WHOM IT MAY CONCERN:

Be it known that I, C. O. HANSEN, of Memphis, in the county of Shelby, and State of Tennessee, have invented a new and useful Improvement in Bevel-Squares; and I do hereby declare that the following is a full, clear, and exact description thereof, which will enable others skilled in the art to make and use the same, reference being had to the accompanying drawings, forming part of this specification.

The nature of my invention relates to an improvement in bevel-squares for joiners' use, and consists in constructing them with two stocks, pivoted to a blade near its centre, and providing the said stocks with links, pivoted to the same, at about their centres, in the direction of their length, the other ends of the said links being joined to a thumb-screw, which slides in a central slot in the end of the blade, which is within the angle formed on the said stocks, the said blade being provided with a scale, on which the sliding head of the set-screw may be set, by tightening up the said screw, at certain points, to mark the proper angles for figures having various numbers of sides.

On reference to the accompanying drawings—

Figure 1 represents a plan of my improved tool, and

Figure 2 an edge view of the same.

Similar letters of reference indicate corresponding parts.

A A represent the stocks, pivoted to the blade B. C C are the links connecting the same with the set-screw D. The end, B, of the blade is provided with a scale, as shown in fig. 1, which, in this example, is arranged to indicate the proper angles of the stocks A A with each other, for marking the sides of any figure having regular sides of any number from three to sixteen. To adjust it to the angle for a figure of any given number within the range specified, the head of the screw D is moved on the scale to the line indicated by the figure corresponding with the given number of sides of the required figure. When the set-screw is tightened up, and the parts secured on that angle, it may also be adjusted to any other angle, as ordinary bevels are. To use it as a right-angled square, the set-screw is moved inward until the stocks A A are brought into a right line, when the set-screw is tightened up, to hold them in that position.

Having thus fully described my improvements, what I claim, and desire to secure by Letters Patent, is—

The bevel-square, constructed as described, and consisting of the graduated plate B, longitudinally slotted, the pivoted arms A, links C, and sliding clamp-nut D, all arranged to operate substantially as herein shown and described.
